UNITED STATES PATENT OFFICE.

EDWARD B. NOWOSIELSKI, OF BLOOMFIELD, NEW JERSEY, ASSIGNOR TO SPLITDORF ELECTRICAL COMPANY, OF NEWARK, NEW JERSEY.

AUDIO-FREQUENCY TRANSFORMER.

Application filed August 22, 1924. Serial No. 733,478.

To all whom it may concern:

Be it known that I, EDWARD B. NOWOSIELSKI, a citizen of the United States, residing at Bloomfield, in the county of Essex, State of New Jersey, have invented certain new and useful Improvements in Audio-Frequency Transformers, of which the following is a description, reference being had to the accompanying drawing and to the figures of reference marked thereon.

This invention relates to an audio frequency transformer especially adapted for use in connection with radio circuits.

It is the object of this invention to provide an audio frequency transformer which will transform the audio frequency currents with minimum distortion.

Another object of my invention is to provide a transformer which is neat in appearance, simple in construction, and hence, cheap to manufacture.

Other objects will be apparent after a study of the drawing taken in connection with the annexed specification, wherein—

Figure 1 is a side view of my complete transformer.

Figure 2 is an end view of Fig. 1 while

Figure 3 is a bottom view of the transformer.

In the following description the same numbers refer to corresponding parts in the various views.

The transformer as illustrated is of the usual type made up of laminations in which the larger one designated by the numeral 1 is substantially E shape with a straight or I shape lamination to complete the magnetic circuit. The laminations 1 are provided with a projection 3, on either end.

These projections serve to increase the area of contact with lamination 2 at the same time they act as a means for clamping the laminations 1 and 2 together through the medium of clamps 4 that pass through the bottom frame member 5. The ends 6 of the clamps 4 are bent over as indicated in Fig. 3, thereby drawing the clamps securely into locking position. In addition to the clamps the cover member 7 has projections 8 on either end which also extend through the bottom frame member 5 and are bent over as indicated at 9. The cover member 7 is used to hold the laminations 1 in place and to act as a cover to present a more finished

appearance of the complete transformer.

Frame member 5 has a portion 15 punched upward into clamp members 10 which engage both sides of the I shaped laminations 2. The primary and secondary windings are included in a coil 11 associated with which is a connecting board 12 having terminals 13 arranged on either side, two for the primary and two for the secondary; holes 14 are used on frame member 5 for mounting the transformer. While I have shown the connecting board 12 between the coil and part of the core structure, it is to be understood that this connecting board may be mounted on the outside of the core in a satisfactory manner.

Other changes in details may be made without departing from the spirit of my invention and the scope of the appended claims.

Having thus described my invention, what I claim is:

1. In a transformer, a core having windings associated therewith, said core having substantially E shaped laminations with projecting ends, bar laminations closing the E, a frame member adjacent the bar laminations and clamps passing over the projecting ends of the E shaped laminations and having parts passing through said frame member and fastened thereto.

2. In a transformer, a core having substantially E shaped laminations with projecting ends, bar laminations closing the E and extending substantially to the end of said projecting ends, a frame member adjacent the bar laminations, and clamps engaging said projecting ends of the E shaped laminations and having parts passing through said frame member.

3. In a transformer, a core having windings associated therewith, said core having substantially E shaped laminations with projecting ends, bar laminations closing the E, a frame member adjacent the bar laminations and having parts extending upward on the outside of said bar laminations and in close contact therewith, and clamps engaging the projecting ends of the E shaped laminations and having parts fastened through said frame member.

4. In a transformer, a core having windings associated therewith, said core having substantially E shaped laminations with projecting ends, bar laminations closing the E, a frame member adjacent the bottom of

the bar laminations, a cover member passing over the outer surface of the **E** laminations and clamps engaging said cover and projecting ends of the **E** shaped laminations and having parts fastened through said frame members.

5. In a transformer, a core having windings associated therewith, said core having substantially **E** shaped laminations with 10 projecting ends, bar laminations closing the **E**, a frame member adjacent the bar laminations, and having parts engaging the outer sides of said group of bar laminations, a cover engaging the outer surface of said 15 **E** shaped laminations, and clamps engaging said cover and projecting ends of the **E** shaped laminations and having parts passing through and fastened to said frame member.
- 20 6. In an audio transformer, a shell type core, windings carried on an arm of the core, said core comprising; **E** and bar shaped laminations with means for increasing the effectiveness of the magnetic joint at the 25 junction of the **E** and bar laminations com-

prising; projecting portions on said **E** shaped laminations, the bar laminations extending substantially to the ends of said projecting portions and means for clamping said projecting ends and bar laminations securely 30 together.

7. In an audio transformer, a shell type core having **E** and bar shaped laminations, windings carried on the central arm of the **E** part of the core, said **E** laminations having portions projecting away from the windings, said bar laminations extending to substantially the end of said projecting portions of the **E** laminations; a frame member having guide and support portions engaging the opposite sides of said group of bar laminations and a cover passing over the **E** shaped laminations including said projecting ends and clamps passing over both cover and projecting ends and having parts fastened to said frame member.

In testimony whereof, I affix my signature.

EDWARD B. NOWOSIELSKI.
